Primary Examiner — Catherine Ho*Assistant Examiner* — Natalya M Rapundalo(74) *Attorney, Agent, or Firm* — JCIPRNET(57) **CLAIM**

The ornamental design for a vacuum bottle, as shown and described.

DESCRIPTION

FIG. 1 is a perspective view of a vacuum bottle showing our new design;

FIG. 2 is another perspective view thereof;

FIG. 3 is a front view thereof, the rear view being a mirror image thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 in FIG. 6; and,

FIG. 9 is a perspective view thereof with the cover opened. The broken lines illustrate portions of the vacuum bottle that form no part of the claimed design.
